INVENTOR
THEODORE COTE
ATTONEY.

UNITED STATES PATENT OFFICE

THEODORE COTÉ, OF OGDENSBURG, NEW YORK, ASSIGNOR TO PALMIRA L. COTÉ, OF HARTFORD, CONNECTICUT

LOCK

Application filed December 24, 1930. Serial No. 504,601.

My invention relates to locks.

It has for its object to provide an improved lock and more particularly, an improved lock of the combination type. A further object of my invention is to provide such a lock having improved mechanism operative on a plurality of bolts and controlled by improved control mechanism. A still further object of my invention is to provide an improved controlling mechanism including a member forming a part of the combination mechanism and both longitudinally and rotatably adjustable into a plurality of control positions relative to the locking means and relative to a protecting means between said positions. These and other objects and advantages of my improved construction will, however, hereinafter more fully appear.

In the accompanying drawing I have shown for purposes of illustration one embodiment which my invention may assume in practice.

In this drawing,—

Figure 1 is a side elevation of a lock mechanism embodying my improvements, a portion of the rotating disc being broken away to facilitate illustration;

Fig. 2 is a view of the back of the mechanism shown in Figure 1, with the back plate removed and certain of the parts shown in section to facilitate illustration;

Fig. 3 is an end view of the construction shown in Figure 1;

Fig. 4 is a sectional view on line 4—4 of Figure 2;

Fig. 5 is a sectional view on line 5—5 of Figure 2;

Fig. 6 is a sectional view on line 6—6 of Figure 2; and

Figs. 7 and 8 are perspective views of details.

In this illustrative construction it will be noted that I have shown a case 1, herein having an inside cover plate 2 connectible thereto by suitable means as, for example, corner screws 3, and such a case housing therein mechanism controlling the operation of bolts 4 and 5 projecting from one end of the case, while the mechanism in the case is controllable by a rotatable member 6 form-

ing part of the combination mechanism and on the outside of the case, and a cooperating inside control member 7 operable through the cover 2.

Referring more particularly to the combination structure operated by the member 6, it will be noted that the latter is in the form of a disc carried on the outer extremity of a shaft 8. This shaft also has fixed to the inner end thereof, as by a set screw 9 received in a suitable slot 10 in the shaft, a rotatable combination member 11. This in turn has a bevelled inner edge 12 carrying a suitable indication or mark 13 movable relative to a suitable dial 14 formed on an annular stationary member 15 attached to the exterior of the case by suitable means, as screws 16. Herein, it will also be noted that the portion 12 on the member 11 projects over the member 15. The member 11 is also provided with a reduced portion 17 rotatable in a corresponding aperture in the member 15, and, further, carries a plate 18 abutting against the inner end of the member 11, which is rotatable in an annular groove in the other face of the plate 15 and attached to the member 11 by suitable means, as screws 19. Thus it will be evident that upon suitable rotation of the member 6, the member 11 may be adjusted so as to bring its mark 13 into any desired relation to the dial 14, while the member 6 may be adjusted longitudinally at will relative to the member 11.

Operatively connected to the combination mechanism is also the mechanism inside the case and controlling the bolt 4. Herein, it will be noted that the shaft 8 has a toothed member 20 connected to its inner end in any suitable manner as by riveting at 21, in such manner as to be both rotatable with the member 6 and shaft 8 and longitudinally movable therewith when the same are shifted longitudinally relative to the member 11. Herein, the inner end of the shaft 8 is also provided with an axial bore 22 adapted to receive a pin 23 suitably fixed on the cover 2 and co-operating with the member 11 in guiding the shaft 8 in its longitudinal movement, while the case 1 is also provided with a portion 24 forming one limit or abutment for

the toothed member 20. Here it will also be observed that when the member 20 rests against this portion 24, its teeth 25 mesh with corresponding teeth 26 formed on a rack member 27 which carries the bolt 4 at one end and is reciprocable in the case 1 relative to suitable guides 28, while the bolt 4 is guided in the front edge of the case. Thus it will be evident that in one longitudinal position of the toothed member 20, rotation of the member 6 in opposite directions will result in projecting or withdrawing the bolt 4.

Co-operating with this bolt operating mechanism I have herein shown improved dogging mechanism controlling the same which, while not required, is desirably used therewith. Here it will be noted that this mechanism is also operable by the member 20. It assumes the form of a co-operating dog 29 pivoted on a suitable pivot member 30 which is, in turn, attached to the case 1 and disposed in a slot 31 extending longitudinally of the member 27 while spaced from the ends of the latter. As shown, this dog is adapted to be swung about the member 30 from the full line position illustrated in Figure 2, wherein it is in back of the bolt 4 and accordingly prevents inward movement thereof and of the member 27, to the dotted line position shown in that figure, wherein the bolt and member 27 may move inward. Herein, in order to move the dog 29 from the full to the dotted line position, or vice versa, the dog 29 is also provided near its pivot with a series of teeth 32 disposed in a plane parallel to the plane of the teeth 26 on the rack member 27 and also adapted to be engaged by the teeth 25 on the member 20. Thus it will be evident that where it is desired to use this dog mechanism, the same may be actuated or released by moving the member 6 longitudinally in such manner as to bring the teeth of the member 20 into engagement with the teeth 32 and then rotating the member 6 in the proper direction to throw the dog or release the same, with these operations preceding or following the operations of the bolt 4 previously described.

Operatively associated with the toothed member 20 is also the operating mechanism for the bolt 5. Herein, it will be noted that the latter is reciprocable through a usual aperture in the front edge of the case and connected at its inner end to a rack member 33 movable in guides 33' on the case and herein laterally offset from the bolt 5 and connected thereto by a relatively transversely disposed portion 34. Here it will also be noted that this portion 34 carries a pin or rod 35 projecting inwardly inside the rack 33. Moreover, it will be noted that this rod is encircled by a suitable coiled spring 36. This spring in turn operates between the portion 34 and a projecting portion 37, on a member hereininafter mentioned, and having an aper-

ture 38 through which the inner end of the rod extends. As shown, the portion 37 also has an upstanding projection 39 (Fig. 4) which is receivable in a suitable longitudinal slot 40 in the inner end of the rack member 33 and forms a guide for the latter. Herein, it will also be noted that a co-operating rack guide and spacing member 41 is held in position by suitable members 42 and carries the projections 37 and 39, while a co-operating member 43 similarly connected to the casing 1 also forms a co-operating guide for the member 33. Attention is also directed to the fact that the rack member 33 is provided with teeth 44 adapted to mesh with the teeth 25 on the member 20, and that it is also provided with the controlling member 7 which has its shank 45 fixed to the member 33 between the member 5 and the slot 40 in the member 33 and projecting out through a longitudinal slot 46 in the cover 2. Thus it will be evident that when the member 20 is adjusted longitudinally by the member 6 into mesh with the teeth 44 on the rack 33, the bolt 5 may be adjusted into or out of locking position by suitable rotation of the member 6, while in other longitudinal positions of the member 20 the bolt 5 will be controllable by the member 7 and form an ordinary spring latch.

Operatively associated with the controlling mechanisms heretofore described, I have also provided improved controlling mechanism adapted to prevent the operation of both bolts 4 and 5 save by one knowing the combination of the mechanism. Herein, this mechanism assumes the form of a controlling member or tooth 47 which projects laterally toward the axis of the member 20 from the free end of a radially located support 48 and terminates short of the axis of the member 20 in a plane between the planes of the rack 33 and teeth 32. Herein, I also provide an aperture 49 in the member 20 adapted to receive the tooth 47 in a certain angular position of the member 20 about its axis and, accordingly, permit passage of the member 20 from the tooth means controlling one bolt to the toothed means controlling the other bolt as the member 6 is moved longitudinally. Thus it will be evident that by reason of the tooth 47 and its co-operating aperture 49 in the member 20, it will be necessary for one to know the proper position of the indicator 13 relative to the combination 14, before it will be possible for him to move the member 20 from operation on one bolt to operation on the other.

Attention here is also directed to the fact that the member 48 is fixed in the inner face of the member 15, while an arcuate slot 50 is provided in the adjacent wall of the case 1 through which the member 48 extends. Herein it will be noted that this arcuate slot 50 extends from a point under the rack 27 (Fig.

2) clear around the member 20 and terminates at a point under the rack 27 on the opposite side of the axis of the member 20. Thus a substantial length of the member 15 is exposed 5 on each side of the axis of the member 20. As a result of this construction it will be evident that a wide range of possible positions is provided for the member 48 in such manner as to enable the combination to be changed 10 readily for different locks by simply locating the member 48 in different positions on the same side or in different positions on the opposite side of the axis of the member 20.

Considering the operation of the mechanism described, let us assume that both bolts 15 are in locking position, and that the dog 29 has been set. In this position of the parts, to unlock the same it is necessary, after pushing in the member 6 to a proper point to 20 cause the member 20 to engage with the teeth 32, to rotate the member 20 to release the dog 29, shift the member 20 slightly reversely longitudinally into engagement with the teeth 26 on the rack 27, rotate the member 20 25 to unlock the bolt 4, shift the member 20 longitudinally out of engagement with the rack 27, rotate the member 20 so that its aperture 49 registers with the tooth 47, then shift it longitudinally past the tooth and into registration with the teeth 44 on the rack 33, and then 30 rotate it to release the bolt 5. In locking the same, it will be evident that the bolt 5, being a spring bolt, will take care of itself, while the bolt 4 will be locked by successively 35 actuating the rack 27 and dog 29. It will also be evident that the member 20 may be left in any of its operative positions or in planes between the planes of its operative positions. It will also be evident that not only may the 40 combination of different locks be varied by varying the location of the member 48 on the member 15, but that whenever it is desired to change the combination of any lock, this may be readily done by changing the position of 45 the member 15 relative to the arcuate slot 50.

It will be evident that the lock is exceedingly safe since the different longitudinal and rotary positions of the control member make it exceedingly difficult for an unauthorized 50 person to get the right combination. On the other hand, to one familiar with the combination, the lock may be unlocked or locked very expeditiously and conveniently. In practice it will of course be understood that 55 the various longitudinal positions of the shaft 8 may be suitably indicated on the latter. It will also be evident that these figures with the rotation figure, which indicates the position wherein the aperture 49 will clear 60 the tooth 47, will constitute a combination of longitudinal and rotary movement easy to remember. Herein, for example, the longitudinal positions in which the member 20 engages with the member 32 and with the teeth 44 of the rack 33, have been indicated by

spaced lines and numerals 2 and 3 on the shaft 8. At the same time it will also be observed that the lock is not only readily openable from the outside by one familiar with the use of the same, but when the bolt 4 is withdrawn and the member 20 is out of engagement with the rack 33, also provides a construction in which the bolt 5 is usable as an ordinary spring latch. These and other advantages of my improved construction will, however, be apparent to those skilled in the art. 70 75

While I have in this application specifically described one embodiment which my invention may assume in practice, it will be understood that the same is shown for purposes 80 of illustration, and that the invention may be modified and embodied in various other forms without departing from its spirit or the scope of the appended claims. 85

What I claim as new and desire to secure by Letters Patent is:—

1. In a combination lock having a case, a plurality of bolt mechanisms therein, operating mechanism therefor including a longitudinally and rotatably adjustable member within said case forming a permanent part of said lock and adapted to co-operate with either mechanism, and means within said case for inhibiting passage of said member from one mechanism to the other save when moved into a predetermined position. 90 95

2. In a lock, a plurality of bolts each provided with a rack member spaced from the other rack member, a co-operating rotatable toothed member engageable at will with different rack members in different positions, and a longitudinally shiftable and rotatable controlling member carrying said toothed member. 100

3. In a lock, a plurality of bolts each having a rack member spaced from the other rack member, a co-operating rotatable and longitudinally movable toothed member engageable at will with different rack members in different positions, and means for 110 requiring predetermined movements of said rotatable toothed member to actuate different rack members. 105

4. In a lock, a bolt having a rack member, a co-operating rotatable toothed member engageable with said rack member, a longitudinally shiftable and rotatable controlling member carrying said toothed member, and dogging means for said bolt likewise operable by said toothed member. 115 120

5. In a lock, a plurality of vertically spaced bolts each having a rack and said racks disposed in laterally offset planes, a rotatable toothed member engageable with said racks in different positions, and a controlling member longitudinally adjustable to adjust said toothed member and rotatable therewith. 125

6. In a lock, a plurality of vertically spaced bolts each having an actuating por- 130

- tion reciprocable therewith and said portions disposed in laterally offset planes, a rotatable member engageable in different positions with said actuating portions, and controlling means between said actuating members and co-operating with said rotatable member requiring different predetermined operations of the latter to actuate different bolts.
7. In a lock, a plurality of bolt members each having an actuating member, a co-operating rotatable and apertured member forming a permanent part of the lock and longitudinally shiftable into engagement with different actuating members, and a stationary member between said actuating members and co-operating with said apertured member passing through the apertures in said rotatable member only in a predetermined rotary position of said rotatable member.
8. In a lock, a plurality of bolt members each having an operatively connected rack member, a co-operating rotatable and apertured toothed member longitudinally shiftable into engagement with the different rack members, and a stationary member between said rack members passing through the aperture in said toothed member only in a predetermined rotary position of said toothed member.
9. In a lock, a spring actuated bolt having releasing means operable from one side of the lock, a co-operating bolt, and operating connections for both of said bolts operative from the opposite side of the lock and having an operating member and co-operating combination presenting means within the lock for inhibiting successive operation of said bolts save upon movement of said operating member in a predetermined sequence.
10. In a lock, a spring actuated bolt having releasing means operable from one side of the lock, a co-operating bolt, and operating connections for both of said bolts operative from the opposite side of the lock and having an operating member forming a permanent part of the lock and both longitudinally and rotatably movable and co-operating combination presenting means for inhibiting successive operation of said bolts save upon movement of said operating member in a predetermined sequence.
11. In a lock, a spring actuated bolt having releasing means operable from the interior, a co-operating bolt, operating connections for the latter operative only from the exterior and comprising a longitudinally and rotatably adjusted control member, and operative connections controlled by said control member for successively operating said bolts upon rotary and longitudinal movement of said control member in a predetermined sequence.
12. In a lock, a spring actuated bolt hav-
- ing releasing means operable from the interior, a co-operating bolt, operating connections for the latter operative only from the exterior and comprising a longitudinally and rotatably adjusted control member, and operative connections controlled by said control member comprising a toothed member movable with said control member and rack members connected to said bolts and engageable with said toothed member in different longitudinal positions of the control member.
13. In a lock, a spring actuated bolt having releasing means operable from the interior, a co-operating bolt, operating connections for the latter operative only from the exterior and comprising a longitudinally and rotatably adjusted control member, operative connections controlled by said control member comprising a toothed member movable with said control member and having an aperture and rack members connected to said bolts and engageable with said toothed member in different longitudinal positions of the control member, and a stationary toothed member receivable in said aperture in said first mentioned toothed member in a predetermined rotary position of the latter.
14. In a lock, a plurality of bolt members each having a rack member, and a co-operating toothed member longitudinally shiftable into engagement with the different rack members, said toothed member having an aperture therein, a co-operating stationary member between said rack members received in said aperture in a predetermined rotary position of said toothed member, spring means connected to one of said rack members, supplementary dog mechanism locking the other rack member and operable by said toothed member, and combination mechanism comprising a dial and a longitudinally adjustable and rotatable controlling member co-operating with said dial and movable with said toothed member.
15. In a lock, a casing having a plurality of bolt apertures in an edge thereof, a plurality of bolts movable in said apertures and each having a rack member guided in the casing, spring mechanism connected to one of said bolt members co-operating to form a spring latch, a toothed locking and releasing dog co-operating with the other bolt member, and a toothed member engageable with said rack members and dog in different longitudinal positions and rotatable to actuate either of the same in either direction.
16. In a lock, a casing having a plurality of bolt apertures in an edge thereof, a plurality of bolts movable in said apertures and each having a rack member guided in the casing, spring mechanism connected to one of said bolt members co-operating to form a spring latch, a toothed member engageable with said rack members in different longi-

tudinal positions and rotatable to actuate the same, and means permitting passage of said toothed member from operative connection with one rack member into operative connection with the other only after rotation of said toothed member into a predetermined rotary position.

17. In a lock, a casing having a plurality of bolt apertures in an edge thereof, a plurality of bolts movable in said apertures and each having a rack member guided in the casing, spring mechanism connected to one of said bolt members co-operating to form a spring latch, a toothed member engageable with said rack members in different longitudinal positions and rotatable to actuate the same, a longitudinally and rotatably adjustable shaft member movable with said toothed member, and co-operating combination means carried by said casing and shaft member including a combination member rotatable with the shaft member while permitting independent longitudinal adjustment of the latter.

25. 18. In a lock, a casing having a plurality of bolt apertures in an edge thereof, a plurality of bolts movable in said apertures and each having a rack connected thereto and guided in the casing, spring mechanism connected to one of said bolt members co-operating to form a spring latch, a toothed member engageable with said rack members in different longitudinal positions and rotatable to actuate the same, a longitudinally and rotatably adjustable shaft member movable with said toothed member, co-operating combination means carried by said casing and shaft member including a combination member rotatable with the shaft member while permitting independent longitudinal adjustment of the latter, a guide carried by said casing and receivable in the inner end of said shaft member, and rotatable guiding means carried by one of said combination members and engageable with the other.

19. In a lock, a casing, a plurality of bolts movable therein, rack members connected to said bolts and guided in said casing, a toothed member engageable with said rack members in different longitudinal positions and rotatable to actuate the same, a longitudinally and rotatably adjustable member movable with said toothed member, co-operating combination means carried by said casing and shaft member including a combination member rotatable with the shaft member while permitting independent longitudinal adjustment of the latter and a co-operating combination member relative to which said first mentioned member is adjustable, and a controlling member carried by said co-operating member and engageable with said toothed member to inhibit longitudinal shifting of the latter beyond said control member save

in a predetermined angular position relative to the latter.

20. In a lock, a casing, a plurality of bolts movable therein, rack members connected to said bolts and guided in said casing, a toothed member engageable with said rack members in different longitudinal positions and rotatable to actuate the same, a longitudinally and rotatably adjustable member movable with said toothed member, co-operating combination means carried by said casing and shaft member including a combination member rotatable with the shaft member while permitting independent longitudinal adjustment of the latter and a co-operating combination member relative to which said first mentioned member is adjustable, a controlling member carried by said co-operating member and engageable with said toothed member to inhibit longitudinal shifting of the latter beyond said control member save in a predetermined angular position relative to the latter, and means for enabling adjustment of said control member to vary the controlling position thereof.

In testimony whereof I affix my signature.

THEODORE COTÉ.
